(No Model.)

G. W. FULLER.

ARMATURE FOR DYNAMO ELECTRIC MACHINES.

No. 286,415.

Patented Oct. 9, 1883.

UNITED STATES PATENT OFFICE.

GEORGE W. FULLER, OF NORWICH, CONNECTICUT.

ARMATURE FOR DYNAMO-ELECTRIC MACHINES.

SPECIFICATION forming part of Letters Patent No. 286,415, dated October 9, 1883.

Application filed August 16, 1883. (No model.)

To all whom it may concern:

Be it known that I, GEORGE W. FULLER, of Norwich, Connecticut, have invented an Improvement in Armatures for Dynamo-Electric 5 Machines, of which the following is a specification.

My invention relates to the class of armatures for dynamo-electric machines in which cores of the armatures are composed of iron 10 spirals, with the object of preventing the existence in the core of any closed circuit in which currents of electricity can be established by induction. It is especially intended for the employment for the core of a cylindrical armature having induction-coils which traverse 15 its exterior longitudinally upon opposite sides.

My invention consists in forming the core of a comparatively thin iron plate in the form of a spiral, which is supported upon the armature-shaft, but preferably insulated therefrom and from the heads by which it is secured in position. By this construction the magnetic field is nearly filled with iron, and yet does not present a continuous circle of 20 metal capable of constituting a closed electrical circuit in which currents of electricity can be established by induction.

Instead of employing a single spiral, I may use two or more spirals of like pitch and diameter, and arrange them in the core with their convolutions relatively interplaced.

A result which approximates that attained by my improvement may be obtained by using for the core a cylinder of iron which is not insulated from the armature-shaft, but which 35 has a deep spiral groove formed in its periphery. The inductive influence which tends to establish currents of electricity is most energetically exerted upon the exterior portion of 40 the core; hence the usefulness of the spiral grooving by which the existence of a closed or continuous electrical circuit in the exterior portion of the core is prevented.

The accompanying drawings, illustrating an 45 armature-core embodying my invention, are as follows:

Figure 1 is an end view. Fig. 2 is a longitudinal section through the line $x-x$ on Fig. 1. Fig. 3 is an elevation showing several convolutions of the spiral detached from the shaft. Fig. 4 is a partial longitudinal section through the line $x-x$ on Fig. 1, showing a modification

of the spacing-strip for separating and insulating the convolutions of the spiral iron plate from each other.

The armature-shaft A is adapted for rotation in the machine in the usual manner. Its central portion is surrounded with the sleeve of insulating material B, outside of which is the iron spiral C. Immediately adjoining the sleeve B is a spiral strip, D, of paper, rubber, or other insulating material, the convolutions of which are interplaced with the convolutions of the spiral plate C, which is intended for employment for the purpose of holding apart 65 or spacing the convolutions of the spiral C, especially when the latter is composed of very thin plates. The spacing-strip D may be narrow, as shown in Fig. 2, so that the air spaces d are established between the convolutions of 70 the plate C; or the strip D may be made of thin material—such as paper—and may be of the same width as the plate C, as shown in Fig. 4.

The spiral plate C is secured in position between the collar E, affixed to one end of the shaft A, and the nut F screwed upon the other end of the shaft, and prevented from being jarred loose by the conically-formed jam-nut f.

The collar E is provided with a conical hub, 80 e, and the nut F has the central portion of its inner face similarly formed, while its exterior face is centrally recessed to receive the conical periphery of the jam-nut f. The latter is provided with the holes f' f' f' f', for the reception 85 of the driver, by which it is screwed on or off the shaft A.

The nut F has four holes tapped through it to receive the steady-screws G G G G, the inner portions of the shanks of which are respectively received within the tubes g' of insulating material, which are inserted, respectively, through holes in two or more of the adjoining convolutions of the spiral plate C. The spiral C is centrally countersunk at each end 95 to enable its end convolutions to clear the peripheries of the hub e and the conical projection of the nut F.

Washers H H' of insulating material are introduced, respectively, between the ends of the 100 spiral G and the inner faces of the collar and the nut F.

It is not deemed necessary to show all the parts of a dynamo-electric machine, nor to in-

dicate the method of applying the induction-coils to such an armature-core, inasmuch as the use of cylindrical armatures in such machines and the method of applying induction-coils to them are common and well known.

By this mode of construction the spiral plate, which constitutes the core, and by which the magnetic field is substantially filled with a mass of iron, is insulated from the shaft and the terminals of the spirals of which the core is composed are insulated from each other, so that the core does not present a continuous circle of metal capable of constituting a closed electrical circuit in which currents of electricity can be established by induction when the armature is employed in a dynamo-electric machine.

I claim as my invention in a dynamo-electric machine—

20 1. A cylindrical armature-core composed of an iron plate or plates formed spirally around the armature-shaft, in combination with induction-coils longitudinally traversing the core upon opposite sides thereof.

2. A cylindrical armature for a dynamo-electric machine having its core composed of a spiral or spirals, of iron plates insulated from the armature-shaft, and having the terminals of the spiral or spirals insulated from each other, for the purpose of substantially filling the magnetic field with iron, while preventing the existence in the core of a closed electrical circuit in which currents of electricity can be established by induction when the armature is employed in the usual manner in a dynamo-electric machine.

3. In a cylindrical armature, substantially such as described, the spacing-strip D, interplaced with the convolutions of the spiral iron plate or plates of which the core is composed, as and for the purposes set forth.

GEO. W. FULLER.
